UNITED STATES PATENT OFFICE

GASTON PARENT, OF PARIS, FRANCE

VANITY CASE

Application filed February 2, 1929. Serial No. 337,129.

My invention relates to a new and improved vanity case.

One of the objects of my invention is to provide an improved vanity case having a plurality of compartments, one of said compartments being slidably mounted upon the other.

Another object of my invention is to provide a vanity case having a main compartment provided with a hinge cover, and having a second or lower compartment slidably connected to the main compartment.

Another object of my invention is to provide a device of the type above mentioned in which a lipstick holder or the like, is slidably connected to the lower or supplemental compartment.

Another object of my invention is to provide a device of this type which shall be simple and economical to manufacture and to use.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a perspective view of the device in the closed position.

Fig. 2 is a perspective view of the device in the open position.

Fig. 3 is a sectional view on the line 3—3 of Fig. 4.

Fig. 4 is a longitudinal central section of the device in the open condition.

Fig. 5 is a longitudinal central section of the device in the closed condition.

Fig. 6 is a sectional view on the line 6—6 of Fig. 4.

Fig. 7 is a sectional view on the line 7—7 of Fig. 4.

Fig. 8 is a perspective view of the lipstick holder.

The device comprises a main compartment 1 having a hollow extension 2 connected to the rear thereof. This hollow extension may be considered as constituting the rear portion 50 of the device, to which the main compartment

1 is secured. The main compartment 1 is provided with an insert 15, which is adapted to hold a cosmetic such as a compact of face powder or the like. For this purpose the rear wall of the insert 15 is provided with a blade 55 spring 12 which is adapted to releasably hold a compact or plaque of face powder or the like. The main compartment is provided with a cover 3 which is connected thereto by means of a hinge 4. The cover 3 is provided with a mirror 6 held therein by a suitable frame.

The supplemental sliding compartment 5 is provided with flanges 14, which cooperate with guides 14^a connected to the underside of the main compartment 1. The bottom of the main compartment 1 is provided with downwardly directed tongues 20 which are preferably stamped out of the bottom of said compartment 1.

For convenience, the device is referred to as being held in the horizontal position, although it is obvious that the operation thereof does not depend upon the position in which it is held.

All the parts, save the mirror 6, are made of any suitable metal. Likewise, the bottom of the main compartment 1 may be continuous with the adjacent partial vertical wall 1^a of the extension 2, as clearly shown in Fig. 5. This partial wall 1^a, which does not extend to the top of rear portion 2, may be considered as constituting a partial lower front wall of said rear portion. The tongues 20 serve to limit the forward sliding movement of the bottom compartment 5. One of the walls of the compartment 5 is perforated so that a lipstick holder 7 can be slidably inserted therein. The bottom compartment 5 is also provided with a partition 16 to form 90 a pocket or sub-compartment in which the lipstick holder case 7 can slidably fit. This partition 16 is provided with an outwardly bent blade spring 16^a which serves to hold a cake or plaque of suitable cosmetic, such as a cake of rouge for example, in said bottom compartment 5. The lipstick holder case 7 is provided with a longitudinal slot 18. The lipstick L is held in the usual inner holder 11 provided with a pin 8 which fits slid- 100

ably in said longitudinal slot 18. Said guide pin 8 is also adapted to fit in the longitudinal recess 9 provided in the bottom of the compartment 5 adjacent the opening in its wall which has been previously mentioned.

5 It is obvious that the lipstick holder 7 can be removed whenever desired without manipulating any other part of the device. Likewise, the compartment 5 may be independently slid forward to utilize the cosmetic therein, and the cover 6 may be opened to independently utilize the cosmetic held in the main compartment.

10 Of course, the main and supplemental compartments could have puffs or pads located therein, in addition to the cakes or placques of cosmetic.

15 The lipstick holder 7 has a frictional fit in the lower compartment so that it cannot fall out.

20 When the device is in the closed position shown in Figs. 1 and 5, the bottom of the lower compartment 5 is at the same level as the bottom of the extension 2 so that a compact and neat device is provided.

25 I have shown a preferred embodiment of my invention, but it is clear that numerous changes and omissions can be made without departing from the spirit of my invention.

30 I claim:

1. A vanity case comprising a rear portion, a main compartment secured to said rear portion and having guide means connected to the underside thereof, a cover hinged to said main compartment, and a slideable compartment located below and slidably connected to said guide means.

2. A vanity case comprising a rear portion, a main compartment secured to said rear portion and having guide means connected to the underside thereof, a cover hinged to said main compartment, and a slideable compartment located below and slidably connected to said guide means, the bottom 45 of the sliding compartment being at substantially the level of said rear portion and the cover being at substantially the level of the top of said rear portion when the cover is in the closed position.

50 3. A vanity case comprising a rear portion having a partial lower front wall to which a main compartment is secured, said main compartment having a cover hinged thereto, said main compartment having a slideable 55 compartment slidably connected to guide means located on said main compartment.

4. A vanity case comprising a rear portion, a main compartment secured thereto, guide means connected to said main compartment, a slideable compartment located below said main compartment and having second guide means adapted to cooperate with the first mentioned guide means, and stop means connected to the bottom of the said main compartment and adapted to limit the forward

sliding movement of the slideable compartment, and a cover connected to the said main compartment.

5. In a vanity case, the combination of a compartment having a partition spaced from one of its walls to provide a sub-compartment for a cosmetic holder case, one of the walls of said sub-compartment having an opening to admit said case, a cosmetic holder slidably located in said case, said case having a longitudinal slot, said holder having a guide pin projecting through said slot, said sub-compartment having a recess in a wall thereof to slidably receive said guide pin, so that said pin serves to guide the sliding movement of said case in said sub-compartment and to guide the sliding movement of said holder in said case.

6. A vanity case comprising a rear portion having a partial lower front wall, a main compartment connected to said partial wall, said main compartment being held perpendicular to said rear portion, an insert located in and connected to said main compartment, a cover hinged to said main compartment, guide flanges connected to the underside of said main compartment, a lower slideable compartment having means adapted to cooperate with said guide flanges, said lower compartment having a lateral partition near the rear wall thereof to form a pocket for holding a receptacle, a lipstick receptacle adapted to be located in said pocket, one of the side walls of said lower compartment having an opening adapted to permit the entry of said receptacle, said lipstick receptacle having a longitudinal slot and a lipstick holder slidably mounted therein, said holder having a guide pin projecting through said slot, the bottom wall of said lower compartment having a recess adapted to receive said pin, the bottom of said lower compartment being substantially flush with the bottom of said rear portion, the said cover when in the closed condition being substantially flush with the top of said rear portion.

In testimony whereof I affix my signature.

GASTON PARENT.
